CLAIM

The ornamental design for an animal body planter or the like, substantially as shown.

DESCRIPTION

FIG. 1 is a front perspective view of an animal body planter or the like showing my new design;

FIG. 2 is a front view;

FIG. 3 is a side elevational view taken from the right of FIG. 1, the side opposite being a mirror image;

FIG. 4 is a back view;

FIG. 5 is a top view.
